ELECTRIC FURNACE RESISTOR ELEMENT

Joseph D. Hanawalt and Lorne A. Matheson, Midland, Mich., assignors to The Dow Chemical Company, Midland, Mich., a corporation of Michigan

Application November 6, 1939, Serial No. 302,964

4 Claims. (Cl. 13—20)

This invention relates to an improved construction for electric furnace resistor elements and to furnaces comprising the new elements.

In the operation of electric resistance furnaces for certain metallurgical processes which are conducted at temperatures well above 1000° C. and in which metal vapors are liberated, considerable difficulty is encountered due to failure of the carbon or graphite resistor elements used for heating the furnace. Not only are the resistors subject to direct chemical attack by the metal vapors and accompanying gases, but more particularly, because of the conducting properties of the vapors, destructive electric arcs occur repeatedly between the resistors and other electrically conducting parts of the furnace. As a result of these occurrences, the useful life of resistor elements in such a furnace is exceedingly short and frequent replacements are required.

The principal object of the present invention, then, is to provide an electric furnace resistor element construction which is not subject to the disadvantages mentioned. Another object is to provide an element which is readily replaceable and in addition is free to move longitudinally and thus is not subject to breakage resulting from expansion or contraction of the element with changes in temperature. Other objects will be apparent from the description.

The resistor element construction according to the invention will be explained with reference to the accompanying drawing, in which—

Fig. 1 is a vertical section of one form of electric resistance furnace embodying the invention; and

Figs. 2 and 3 are vertical sections of furnaces embodying other forms of the invention.

The furnace shown in Fig. 1 consists of a metal shell 11 within which is a graphite furnace chamber 12 supported on refractory bricks 13, the space between the shell and the chamber being filled with electrically non-conducting thermal insulation 14. Material may be charged into the furnace and withdrawn therefrom through suitable openings not shown. Extending through the furnace chamber 12 is a cylindrical graphite protection tube 15 which makes firm electrical and mechanical contact with the end walls of the chamber at suitable joints 16. Mounted within the protection tube and spaced therefrom is a cylindrical graphite resistor rod 17, each end of which fits into a recessed graphite terminal block 18. These terminal blocks, which may be water-cooled, if desired, extend outwardly through openings in the ends of the shell 11 to make con-

nection with electric power leads 19. The terminal blocks 18 are separated from the shell and supported by gas-tight bushings 20 and 21, of which one 20 is of insulating material such as 5 Alundum, and the other 21 may be either of insulating or more commonly of conducting material, depending upon whether it is desirable to ground a resistor terminal on the shell 11. The resistor rod 17 is held in place within the protection tube 15 at one end thereof by an insulating bushing 22 and at the other end by a similarly shaped bushing 23 of either insulating or 10 preferably of conducting material, depending upon whether the protection tube 15 and the furnace chamber walls 12 in contact therewith are to be grounded on a terminal block 18.

It will be observed that in the construction described, the protection tube 15 serves to protect the resistor rod from contact with any gases or 15 vapors which may be in the furnace chamber. Because of the electrical interconnection of the protection tube with the furnace chamber wall, and also with one end of the resistor if desired, the tube remains at essentially the same potential as the walls of the furnace chamber; arcing does not occur. In addition, the protection tube and resistor element are free to slide longitudinally relative to one another and to the walls of the furnace, so that expansion changes are compensated.

In the alternative construction shown in Fig. 2, the graphite protection tube 15 is secured electrically and mechanically to the side wall of the furnace chamber 12 at a single joint 16, and extends into the chamber as a cantilever. Within 20 the tube 15 and spaced therefrom is the resistor rod 17, which in this instance fits into only one terminal block 18 extending outwardly through an insulating bushing 20 mounted in the shell 11 to an electrical lead 19. The resistor 17 is held in place and insulated from the protection tube 15 at its end nearest the shell by an insulating bushing 24. At the other end of the protection tube, however, the resistor 17 is connected electrically to the tube by means of a graphite plug 25 which fits snugly into the end of the tube and has a central recess 26 adapted to receive the end of the resistor. The furnace chamber wall 12 is grounded on the shell 11 by a connector bar 27 25 which extends through the shell to provide a terminal 28 for an electrical lead 19. In operation, the electric current passes from the terminal block 18 through the resistor bar 17, and returns through the plug 25, protection tube 15, furnace wall 12, and connector 27. The resistor

11 has an electrical resistance very large in comparison to that of the remaining parts of the electrical circuit, and hence is, practically speaking, the heating element, the other parts serving merely as electrical leads.

In another form of the invention shown in Fig. 3, the construction is very similar to that in Fig. 2. The protection tube extends entirely through the furnace chamber 12, and is secured electrically to the walls thereof at joints 16. Two resistor rods, insulated from the protection tube by Alundum bushings 24, are used. These rods extend into a graphite plug or bushing 29 mounted securely in the center of the tube 15, and adapted to receive the ends of the rods 17.

In the constructions shown in Figs. 1-3, the protection tube and resistor are in electrical contact at only one position along the length of the latter, this contact serving to maintain the two elements at nearly the same potential. In Figs. 2 and 3, the tube is electrically in series with the resistor rod and serves as a power lead therefor, and hence has a potential drop along its length, which, however, is small because of the relatively low resistance. There is accordingly very little potential between the electrically conducting furnace walls and any point on the protection tube. Even in furnaces containing metal vapors at low pressures, arcing does not occur to any significant extent. The elements of Figs. 2 and 3 are 30 easily replaceable.

In furnaces, according to the invention which are to be used in metallurgical processes at temperatures above 1000° C., the resistor rods, protection tubes, and furnace chamber walls are 35 ordinarily constructed of some form of carbon, preferably graphite. However, for operation at lower temperatures, the resistors, tubes, and furnace walls may be made of other electrically conducting materials, and need not all be of the same material.

It will be appreciated that the principle of the invention may be employed in forms other than those illustrated. Thus, more than one resistor may be placed within the protection tube. The resistor construction may be mounted vertically as well as horizontally. The resistor and protection tube may be embedded in recesses in the furnace chamber walls, or the walls themselves, if suitably thick, may be used to form part 50 or all of the protection tube. Other such variations within the scope of the appended claims will doubtless occur to one skilled in the art.

We are aware that others have previously mounted electric furnace resistor elements 55 within refractory protection tubes, and we make no claims broadly to such structure.

What we claim is:

1. In an electric resistance furnace including

a furnace shell having mounted therein a furnace chamber having electrically conducting walls, a resistor construction comprising an electrically conducting protection tube extending

5 into the furnace chamber and in electrical contact with a wall thereof, a resistor mounted within the protection tube and spaced therefrom, electrical contact means connecting the protection tube and the resistor at only one position 10 along the length of the latter, and means for connecting the resistor and protection tube in series across a source of current.

2. In an electric resistance furnace including a furnace chamber having graphite walls, a resistor construction comprising a graphite protection tube extending into the furnace chamber and mounted securely in a wall thereof in electrical contact with the wall, an insulating bushing fitted into the protection tube at a position near the furnace wall and a graphite bushing fitted into the tube at a position remote from the insulating bushing, a graphite resistor rod within the protection tube, being spaced therefrom and mounted firmly in said bushings, and means for connecting the resistor and protection tube in 20 series across a source of current.

3. In an electric resistance furnace including a furnace shell having mounted therein a furnace chamber having carbon walls, a resistor construction comprising a carbon protection tube extending into the furnace chamber and mounted securely in a wall thereof in electrical contact with the wall, an insulating bushing fitted into the protection tube at a position near the furnace wall and a carbon bushing fitted into the tube at a position remote from the insulating bushing, a carbon resistor rod within the protection tube, being spaced therefrom and mounted firmly in said bushings, and means for connecting the resistor and protection tube in 30 series across a source of current.

4. In an electric resistance furnace including a furnace shell having mounted therein a furnace chamber having electrically conducting walls, a resistor construction comprising an electrically conducting protection tube extending into the furnace chamber and in electrical contact with a wall thereof, a resistor mounted within the protection tube and spaced therefrom, electrical contact means connecting the protection tube and the resistor at only one position along the length of the latter, and electric terminals secured one to the resistor and the other to the furnace chamber wall for connecting the resistor and protection tube in series across a source of current.
